AUTOMATIC VOLUME CONTROL

Edward T. Dickey, Philadelphia, Pa., assignor
to Radio Corporation of America, a corpora-
tion of Delaware

Application September 26, 1930, Serial No. 484,510

3 Claims. (Cl. 250—20)

The present invention relates to sensitivity control, and more particularly to novel methods of regulating the gain in high frequency amplifiers.

In congested radio districts, such as large cities, where antennae are in close proximity on house tops, a problem arises which affects radio reception. Due to the tuning of these various antennae, extensive local variations in field intensity occur in such congested areas, resulting in annoying receiver output intensity fluctuations. Again, variations in the transmission medium itself may give rise to similar output changes, as for example in phenomena known as "swinging" and "fading".

Other possibilities causing such reception fluctuation may reside in carrier amplitude decrease; structural shielding of loop antennae when the receiver is portable, as when installed in an automobile, and other similar phenomena sporadically varying the signal output of a receiver. As is well known, various arrangements have been proposed to minimize the fluctuations in receiver output already referred to.

Now I have devised a novel and simple method of eliminating, or minimizing, the output signal variations in a radio receiver which ordinarily result from local field variations and the other causes enumerated. Briefly, variations in the strength of the incoming carrier wave are utilized to control the gain of the amplifier stages so as to counteract the effect of the variations.

Accordingly, it is one of the main objects of the present invention to control the gain of a high frequency amplifier by utilizing the steady component of the rectified output of the amplifier to regulate the amplification of the amplifier in such a sense that variations in the transmission medium are effectively counteracted.

Another important object of the invention is to provide in a radio receiver, a device for giving automatic or semi-automatic control of signal volume, by utilizing the detector plate current in such a manner as to produce a varying bias potential on the control electrode of one, or more, of the amplifier tubes preceding the detector.

Another object of the invention is to provide a radio receiver provided with means for automatically minimizing effects due to incoming carrier wave variations by utilizing such variations to produce varying voltage drops across an impedance disposed in the output circuit of the detector stage, and subsequently using the aforementioned voltage variations to control the operation of the radio frequency amplifier stage, or

stages, in such a direction as to counteract the effect of said carrier wave variations.

Still other objects of the invention are to improve generally the simplicity and efficiency of amplifier gain controls, and to particularly provide an automatic control device of signal volume in a radio receiver which is not only reliable in operation, but economically installed in a radio receiver.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 diagrammatically shows a receiver circuit embodying the invention,

Fig. 2 diagrammatically shows a modification thereof,

Fig. 3 diagrammatically shows another modification of the invention,

Fig. 4 diagrammatically shows still another modification of the invention.

Referring to the accompanying drawing in which like characters of reference indicate the same parts in the different figures, Fig. 1 shows a receiving circuit of the well known and conventional tuned radio frequency type wherein a grounded antenna circuit A, G is coupled, as at M, to the tuned input circuit of an electron discharge tube 1. The input circuit of the tube is tuned by a variable capacity 2, while the output circuit of the tube is coupled, as at M₁, to the tuned input circuit of a second electron discharge tube 3, the tuned input circuit of the second tube being tuned by a second variable condenser 4.

The output circuit of the tube 3 is coupled, as at M₂, to the tuned input circuit of a detector stage embodying an electron discharge tube 6, the detector input circuit being tuned by a variable condenser 5. The variable condensers 2, 4 and 5 are designed for uni-control operation by a mechanism 7 conventionally shown in dotted lines. In view of the fact that the structure briefly described heretofore is very well known to those skilled in the art, it is not believed necessary to go into any further details as to the particular arrangement of the tuned stages.

The anodes of tubes 1 and 3, it being pointed out that tubes 1, 3 and 6 need not be of the triode

type as shown but may be of the screen grid or indirectly heated cathode types if desired, are energized from a source of direct current B, the positive terminal of the source being connected to the 5 primary coil of the coupling M₂, and being connected to the primary coil of the coupling M₁ through a lead 8. The negative terminal of the source B is connected to the cathodes of tubes 1 and 3 by a lead 9, it being observed that both 10 of these cathodes are connected by a lead 10 to each other and to the cathode of the tube 6.

The control electrodes of tubes 1 and 3 are connected by a lead 11 to the positive terminal of a source of direct current V, the negative terminal 15 of the latter being connected by a lead 12 to the negative terminal of a source B₁, the latter source functioning as the energizing source for the anode of tube 6. The positive terminal of the source B₁, is connected to the anode of the tube 6 20 through the primary coil 13 of the audio transformer M₃, and the capacity 14 is shunted across from plate to cathode of tube 6 to by-pass radio frequency current around the transformer primary coil 13 and the source B₁. It will be understood that detection is secured in the 25 detector stage by means of the well known capacity and grid leak arrangement 15 in the control electrode circuit of the tube 6.

As is well known, the output of the detector 30 stage is impressed, through the audio transformer M₃ upon a subsequent utilization means, the latter being of any well known type such as subsequent audio amplification stages and/or a loud speaker. To provide for the regulation of the 35 gain control of the present invention, there is provided a variable resistance R connected between the negative terminal of the source B₁ and the cathode of tube 6, a capacity C being shunted across the variable resistance R.

40 Since the detector anode current is in large part a function of the strength of the incoming carrier wave, at least for carriers of not too great strength, the variation in this anode current is utilized to produce varying voltage drop across the ohmic resistance R. This latter varying voltage drop is utilized to produce a varying bias potential on the control electrodes of the tubes 1 and 3; that is on one, or more, of the amplifier stages preceding the detector. The circuit is 45 so arranged that an increasing signal, which produces a decrease in detector anode current, will lower the amplification obtained from the preceding tube, or tubes, thus causing the signal reaching the detector to decrease.

50 By properly proportioning the resistance R in the detector circuit, as well as its anode current, a good degree of control may be obtained. By making the resistance R variable, the degree of 55 automatic control is varied. The potential drop 60 across the resistance R has the polarity indicated across the capacity C. If the detector anode current drops, this potential decreases and the result is a greater positive potential on the pre-detector 65 amplifier control electrodes due to the source V. Thus, the amplification of these stages is decreased. The capacity of the condenser C should be large enough to by-pass all necessary frequencies around the resistance R.

70 Furthermore, the anode potential B of the amplifier stages, should be not greater than 45 volts because of the positive potential on the control electrodes of the tubes of these stages. It will, also, be noted that the anode source used for the 75 detector stage must be entirely separate from the other source used for supplying anode potential

for the other tubes, since it has the resistance R between its negative terminal and the cathode circuit.

In Fig. 2 there is shown a modification of the invention, embodied in the same type of circuit, although simplified to a greater extent, as shown in Fig. 1. In this modification, the control electrode of the pre-detector amplifier tube 3 is biased negatively by a source 20, and this negative bias is varied in the same manner as in the case of the positive system in Fig. 1. In this modification, the positive terminal of the source 20 is connected by a lead 21 to the cathode of the detector tube 6, the control electrode of the latter being connected to the lead 21. The latter lead 15 is also connected to one terminal of the variable resistance R, the negative terminal of the source B₁ and the opposite terminal of the variable resistance R being connected by a lead 22 to the cathode of the pre-detector amplifier tube 3. 20

In this modification, it is not necessary to provide a separate source of anode potential B₁ for the detector tube; in fact a common anode source may be used, but it is necessary to provide a separate cathode heating supply 23 for the cathode 25 of the detector tube. If the indirect heater type of tube is used for the detector and amplifier tubes, a common heater supply is permissible with the cathodes connected to the necessary different points in the circuit. However, due to the 30 use of a negative potential on the pre-detector amplifier tube 3, or the tube 1 which is to be understood as omitted only for the sake of simplicity, the anode potential for these tubes need not be limited to 45 volts. If the anode potential 35 for tube 3 is higher than that desired for detector tube 6, the anode supply for tube 6 may be tapped off at the necessary point along the anode supply source.

In the modification shown in Fig. 2, the amplification of the pre-detector stage, or stages, is varied by varying the working position along their grid potential-plate current curves, thus changing the slope at the working position. While I have specifically shown a radio receiver 40 of the tuned radio frequency type, it is to be understood that the invention is not limited to any particular type of pre-detector amplifier, nor to amplifier stages coupled as shown in Figs. 1 and 2. These amplifier stages may be of the 45 radio frequency type or intermediate frequency type, and may be tuned or untuned, or any of the usual combinations of these types.

50 Thus, in Figs. 3 and 4 there are shown modified forms of the invention, the figures showing the 55 application of this same type of automatic volume control to a bias type detector. In this case the source 17 provides negative bias potential for the control electrode of the detector tube 6. The 60 action of the circuits shown in Figs. 3 and 4 is now described.

In Fig. 3 the same cathode source can be used for detector and radio frequency tube even if these tubes are of the filament type, but separate anode supply sources must be used. The anode current of the detector tube 6 increases as the 65 strength of the incoming signal increases, and this causes a rise in the voltage drop produced across the resistor R. This potential adds to the negative bias supplied by source 20 in the control 70 circuit of tube 3, thus decreasing the amplification of this tube, as in the case shown in Fig. 2.

In Fig. 4 an arrangement using the bias type detector applied to a circuit is shown in which the increasing incoming signal causes an increase- 75

ing positive potential to be placed on the control electrode of tube 3. Its amplification is therefore decreased in the same manner as in the case of the circuit shown in Fig. 1. In the circuit of Fig. 5 4, the anode supply source can be common, or a portion of it can be common to both anode circuits, but the cathode supply sources must be separate for the two tubes if the filament type of tube is used. In Fig 4, the control electrode bias 10 potential source 20 should be negative to a small degree only, so that the amount of potential produced across resistor R will be sufficient to cause the control electrode of tube 3 to be positive to a relatively high value when a strong signal is received.

In order to enable those skilled in the art to more thoroughly design circuits embodying the invention, the following mathematical formulae 20 are utilized to elucidate the laws governing the phenomena taking place in the circuits.

In the formulae given below the following symbols are used to designate the various electrical values in the circuit:

E_g =Constant voltage supplied by fixed source 25 to control electrode of amplifier tube.

V_g =Necessary voltage on control electrode of amplifier tube to bring amplification to lowest desired level.

v_g =Necessary voltage on control electrode of 30 amplifier tube to give maximum amplification.

R =value of resistor R in anode circuit of detector tube.

I =Normal anode current of detector tube with no incoming signal.

i =That change in detector anode current which 35 accompanies the permissible uncontrolled increase in output signal intensity, and which is necessary in order to provide the controlling change in voltage drop across the resistor R.

The relation between the above symbols is given 40 below for the four circuits described in Figs. 1 to 4.

For Fig. 1 where v_g is nearly zero, or slightly negative, and V_g is positive

$$v_g = E_g - IR \\ V_g = E_g - (I - i) R$$

For Fig. 2 where V_g and v_g are both negative

$$v_g = IR - E_g \\ V_g = (I - i) R - E_g$$

For Fig. 3 where V_g and v_g are both negative

$$v_g = -E_g - IR \\ V_g = -E_g - (I + i) R$$

For Fig. 4 where v_g is probably slightly negative, and V_g is positive

$$v_g = IR - E_g \\ V_g = (I + i) R - E_g$$

Furthermore, it is to be understood that the anode and other voltage supply sources, which are shown by means of the standard battery designation symbol in the figures, can be interpreted as

another type of supply source such as a socket power unit or motor generator without special mention of this in the text. While I have indicated and described several systems for carrying my invention into effect, it will be apparent to one skilled in the art that my invention is by no means limited to the particular organizations shown and described, but that many modifications may be made without departing from the scope of my invention as set forth in the appended claims. 10

What I claim is:

1. In combination, in a radio receiver, a radio frequency amplifier comprising an electron discharge tube provided with an input and output circuit, a current source for energizing the anode of the tube, means for normally positively biasing the control electrode of the tube, a detector comprising an electron discharge tube having its input circuit coupled to the amplifier output, said detector being of the type including a leaky condenser in its grid circuit, a current source for energizing the anode of the detector tube, a common conductive path including an impedance connected directly between the low potential side of the last source and the cathodes of said tubes, 20 and a conductive path connected directly between the low potential side of the biasing means and the low potential side of the impedance.

2. In combination, in a radio receiver, a radio frequency amplifier comprising an electron discharge tube provided with a signal input circuit and an output circuit, a current source for energizing the anode of the tube, means for positively biasing the control electrode of the tube, a detector comprising an electron discharge tube 30 having a tuned input circuit coupled to the amplifier output circuit, a current source for energizing the anode of the detector tube, a common conductive path including an adjustable resistor connected directly between the low potential side of the last source and the cathodes of said tubes, 40 and a conductive path connected directly between the low potential side of the biasing means and the low potential side of the impedance, said detector being of the leaky grid condenser type.

3. In combination in a radio receiver, means for collecting signal energy, said means being subjected to variations in local field intensity, a stage of radio frequency amplification coupled to said collecting means and including an electron discharge tube provided with a control electrode, a cathode, and an anode, a detector stage coupled to the anode circuit of said amplifier stage, the detector stage including an electron discharge tube provided with an input circuit and output circuit and a leaky grid condenser in its input circuit, a source of positive biasing potential connected between the control electrode of said amplifier tube and the output circuit of said detector tube, and a variable resistor in the detector output circuit connected between the negative side of the biasing source and the cathodes of the amplifier and detector tubes for controlling the biasing action of said source on the amplifier control electrode.

EDWARD T. DICKEY. 65
